United States Patent Office

Des. 194,088
Patented Nov. 13, 1962

194,088

HOLDER FOR CIGARS

Ralph Mann, 64 Mallory Road, Tonawanda, N.Y.

Filed Sept. 20, 1961, Ser. No. 66,771

Term of patent 14 years

(Cl. D85—8)

Fig. 1.

Fig. 2.

Fig. 3.

Fig. 4.

FIG. 1 is a top plan view of a holder for cigars embodying my new design, the opposite bottom plan view being substantially the same.

FIG. 2 is a side elevational view thereof, the opposite side elevational view being substantially the same.

FIG. 3 is a front elevational view thereof.

FIG. 4 is a rear elevational view thereof.

I claim:

The ornamental design for a holder for cigars, substantially as shown and described.
